ARTHUR J. FAUSEK AND CARL A. FRAHM, OF ST. LOUIS, MISSOURI.

VALVE.

1,128,302.

Specification of Letters Patent. Patented Feb. 16, 1915.

Application filed January 29, 1912. Serial No. 674,033.

To all whom it may concern:

Be it known that we, ARTHUR J. FAUSEK and CARL A. FRAHM, citizens of the United States, and residents of the city of St. Louis 5 and State of Missouri, have invented certain new and useful Improvements in Valves, of which the following is a full, clear, and exact description, reference being had to the accompanying drawings, forming a part of 10 this specification.

Our invention relates to a valve constructed to receive both a supply of water and a supply of steam with provision for the mixture of the steam with the water to 15 raise the temperature of the latter and deliver from the valve hot or warm water of a temperature suitable for use in lavatories, baths, or for any purpose for which heated water is required. The valve is also so made 20 as to permit the discharge of cold water only.

Figure I is a vertical section taken centrally through our valve. Fig. II is a horizontal section taken on the line II—II, Fig. 25 I. Fig. III is a horizontal section taken on line III—III, Fig. I.

In the drawings: 1 and 3 designate, respectively, water and steam pipe connection members, through which the supplies of 30 water and steam to be mixed in our valve pass, the connection member 1 being provided with a ported diaphragm 2, and the member 3 with a ported diaphragm 4.

5 designates the main shell of our valve, 35 provided with a neck 6, to which the water pipe connection member 1 is joined, and with a neck 8 to which the steam pipe connection member 3 is joined. The neck 6 has communication by a port 7 with a water receiving compartment 10 in the shell 5, and the neck 8 has communication by a port 9 40 with a steam receiving compartment 11 in said shell. Flow of water into the water receiving compartment 10 is controlled by a spring 45 pressed valve 12 carried by a valve stem 13 that extends into said compartment, and flow of steam into the steam compartment 11 is controlled by a spring pressed valve 14 carried by a valve stem 15 that extends into the last named compartment. Intermediate of the two compartments 10 and 50 11 is an outlet compartment 16 having an escapeway 17 that may be located within a spout or nipple of any suitable design.

55 18 designates a main valve operating stem

rotatably mounted in the valve shell 5, and provided with a handle 19 by which said stem may be rotated.

20 designates a valve housing that extends from the water receiving compartment 10 60 to the steam receiving compartment 11 and is rotatably arranged in diaphragms 21 and 22 which are respectively interposed between the water compartment and the outlet compartment 16 and the steam compartment and 65 said outlet compartment. The valve housing 20 is connected at its upper end to the main operating stem 18 and is provided with two peripheral cams 23, (see Fig. II), adapted to engage the inner end of the valve 70 stem 13 to unseat the valve 12. At the lower end of the valve housing 20 is a peripheral cam 24, (see Fig. III), that is adapted to engage the inner end of the valve stem to unseat the valve 14. In the valve housing 75 20 at its upper end are ports 25 through which water entering the compartment 10 may pass into a chamber 26 at the upper end of said valve housing.

27 designates a plunger operable in the 80 valve housing chamber 26 and extending into a mixing chamber 28 beneath the chamber 26, the said plunger being normally maintained in an upwardly adjusted position by a spring 29, and being adapted to be 85 moved downwardly from said position by the pressure of water entering the chamber 26 from the chamber 10. At the lower end of the valve housing 20 is a ported member 30 having a port that furnishes communication 90 between the steam compartment 11 and the mixing chamber 28, this ported member being provided with a valve seat 31 which faces the steam compartment, and also with a valve seat 32 which faces the mixing chamber 95 28.

33 designates a steam cut off valve movable to and from the valve seat 31, and by which flow from the steam compartment 11 to the mixing chamber 28 may be prevented. 100 The valve 33 is carried by a stem 34 connected to the plunger 27 and is moved from its seat upon downward movement of said plunger, due to water pressure thereagainst, and provision is thus made for the entrance 105 of water into the mixing chamber 28 past said plunger and the entrance of steam into said mixing chamber past said valve 33, in order that the water and steam may be mixed, with the result of the temperature 110

of the former being raised by the latter. The steam in its entrance into the mixing chamber flows through the port in the ported member 30 past the valve seats 31 and 32, and the mixing of the two fluid bodies is facilitated by the use of an annular separator 35 in the mixing chamber provided at its lower end with ports 36. The water admitted to the mixing chamber descends 5 around said separator, passes to the interior thereof through said ports through which it is sucked by the steam, in its upward passage through the port in the member 30, the steam and water being thus brought into 10 intimate contact, and the water being heated by the contact with steam, passes upwardly to and over the open top of said separator into the outer portion of the mixing chamber. The heated water then escapes from 15 said mixing chamber through ports 37 in the wall of the valve housing 20, and through a ported retarding ring 38 into the discharge chamber 16. The retarding ring 38 serves as a breaker to check the velocity of 20 flow of hot water as it passes from the mixing chamber of the valve to the discharge chamber so that the water discharged from the valve will flow in an even and steady stream instead of in an agitated condition, 25 30 as it would be if discharged at a high velocity.

One of the very important features of our present invention is the compensating valve 39 that controls the admission of steam into 35 the mixing chamber 28. This compensating valve normally rests upon the valve seat 32 to which it is held by a spring 40, which is also the means provided for maintaining the plunger 27 in its normal position. When the 40 steam cutoff valve 33 is opened to permit passage of steam from the steam receiving compartment 11 to the mixing chamber 28, the steam presses against the compensating valve 39, and acts to move said valve from 45 its seat, and it will be apparent that the compensating valve will only be opened to a degree commensurate with the pressure of steam thereagainst; and, further, that it prevents the flow of water from the mixing 50 chamber into the steam receiving compartment 11, in the event of there being insufficient pressure of steam to unseat the compensating valve. If the pressure of steam is sufficient to unseat the valve, the flow of 55 steam acts to prevent the passage of water into the steam receiving compartment while the compensating valve is open.

It is quite desirable in valves of the kind to which our invention relates to regulate 60 the delivery of steam and water, respectively, to the receiving compartments, in order that the proper supply of each may be accomplished without either being in excess of what it should be. To furnish such regulation, we utilize conical controller members

on the valve stems 13 and 15 that occupy positions in the ported diaphragms 2 and 4. These controllers are adjustably fitted to the valve stems and may, therefore, be adjusted at will to vary the volume of fluid 70 permitted to pass through said diaphragms.

The V-shaped or tapered ports in the upper end of the plunger 27 gradually increase in width from their inner ends to their outer ends, hence a differential flow of 75 water into the mixing chamber is permitted; and by making these ports of the proper dimensions, the admission of water to the mixing chamber may be automatically regulated to insure a proper mixture of water 80 and steam. This automatic regulation of the water flowing through the tapered ports is a quite important feature, inasmuch as the quantity of water entering the mixing chamber should be greatly increased as the 85 plunger 27 moves downwardly, and the desired increase is provided for by the ports at the upper end of the plunger 27. It will be noted that the plunger 27 constitutes a regulator valve whereby the desired mixture 90 of steam and water is positively maintained at all times, regardless of the quantity of water flowing through the discharge spout 17.

We claim:—

1. In a valve, a shell having a mixing 95 chamber, means for delivering water and steam separately to said mixing chamber, and means, operable by the pressure of steam passing to said mixing chamber, for regulating the admission of the steam to 100 said mixing chamber.

2. In a valve, a shell having a mixing chamber, means for delivering water and steam separately to said mixing chamber, and a compensating valve, operable by the 105 pressure of the steam passing to said mixing chamber, for regulating the admission of the steam to said mixing chamber.

3. In a valve, a shell having a mixing chamber, means for delivering water and steam separately to said mixing chamber, and a spring controlled compensating valve, operable by the pressure of the steam passing to said mixing chamber, for regulating the admission of the steam to 110 said mixing chamber.

4. In a valve, a shell provided with a water compartment and a steam compartment and having a mixing chamber therein, means for controlling the delivery of water 115 and steam to said mixing chamber, and means operable by steam pressure for regulating communication between said steam compartment and mixing chamber.

5. In a valve, a shell provided with a 120 water compartment and a steam compartment and having a mixing chamber therein, means for controlling the delivery of water and steam to said mixing chamber, and a compensating valve adapted to be

operated by steam pressure for regulating communication between said steam compartment and mixing chamber.

6. In a valve, a shell provided with a water compartment and a steam compartment and having a mixing chamber therein, means for controlling the delivery of water and steam to said mixing chamber, and a spring controlled compensating valve for regulating communication between said steam compartment and mixing chamber.

7. In a valve, a shell provided with a water compartment, a steam compartment, and having a mixing chamber therein, a valve for permitting admission of steam from said steam compartment to said mixing chamber, a plunger by which said valve is operated, the plunger being operable by pressure from said water compartment and controlling communication between the water compartment and said mixing chamber, a compensating valve regulating communication between said steam compartment and mixing chamber, and a spring 25 interposed between said compensating valve and plunger.

8. In a valve, a shell provided with a water compartment and a steam compartment, a rotatable valve housing within said shell having communication at one end with said steam compartment and at the other end with said water compartment, a valve for permitting the passage of steam from

said steam compartment into said valve housing, a plunger in said valve housing 35 for operating the valve by which the passage of steam is controlled, the said plunger also controlling the passage of water from said water compartment to the interior of said housing, and means operable 40 by said rotatable housing for controlling the delivery of water and steam to said compartments.

9. In a valve, a shell provided with a water compartment and a steam compartment, a rotatable valve housing within said shell having communication at one end with said steam compartment and at the other end with said water compartment, a valve for permitting the passage of steam 45 from said steam compartment into said valve housing, a plunger in said valve housing for operating the valve by which the passage of steam is controlled, the said plunger also controlling the passage of water 50 from said water compartment to the interior of said housing, valves controlling the delivery of water and steam to said water and steam compartments, and cams carried 55 by said rotatable housing for operating the last mentioned valves.
